UNITED STATES PATENT OFFICE.

TURNER C. RUSH, OF LEXINGTON, KENTUCKY, ASSIGNOR TO FREDRIC GRANT ERD,
OF LEXINGTON, KENTUCKY.

BOTTLE-CAP REMOVER.

Application filed October 11, 1922. Serial No. 593,877.

To all whom it may concern:

Be it known that I, TURNER C. RUSH, a citizen of the United States, and a resident of Lexington, in the county of Fayette and 5 State of Kentucky, have invented a new and Improved Bottle-Cap Remover, of which the following is a full, clear, and exact description.

This invention relates to improvements in 10 devices for removing bottle closures, and has particular reference to a device of this character which may be permanently attached to a support.

An object of the invention is to provide a 15 bottle cap remover of extremely simple and effective construction, which may be readily attached to a support and positioned in such manner that, when not in use, will occupy a minimum space and form no outwardly extending projections beyond the base of the device.

The above and other objects will appear more clearly from the following detail description, when taken in connection with 20 the accompanying drawing, which illustrates a preferred embodiment of the inventive idea.

In the drawing—

Figure 1 is a vertical longitudinal section 25 through the device, showing the same in operative position;

Figure 2 is a transverse section through the device in its inoperative position;

Figure 3 is a front elevation of the device 30 in its inoperative position; and

Figure 4 is a perspective view of the closure removing member employed in connection with the invention.

Referring more particularly to the drawing, the numeral 5 indicates a base plate, preferably of rectangular formation and made of any suitable material, said plate being provided at its corners with openings for receiving suitable fastening devices 6 40 utilized to secure the device to a support 7. The central portion 8 of the base plate 5 is offset to form a compartment 9 between the support 7 and said portion 8 and the outer surface of the portion is roughened or corrugated for the dual purpose of providing a match scratching surface and a means for preventing slipping of the bottle cap 10 when the same is being removed from the bottle.

Cooperating with the base plate 5 is a

closure removing member 11 formed of a flat plate of any suitable material and having one end bent upon itself to provide a cap engaging flange 12. The other end of the member 11 is provided with oppositely disposed projections or lugs 13, which form pivots for the member 11 and which limit the pivotal movement of said member in one direction with respect to the plate 5.

The member 11 is mounted for longitudinal movement with respect to the plate 5 and when in its inoperative position, as shown in Figures 2 and 3, said member is recessed within the compartment 9 with the free edge of the flange 12 engaging the bottom edge of an opening 14 formed in the upper end of the offset portion 8 of the plate 5, said portion 8 being reduced or cut away, as indicated at 15, to form said opening. The width of the opening 14 is substantially the same as that of the member 11 so that the side edges forming said opening provide a guide for said member when the same is moved longitudinally with respect to the base plate.

The offset portion 8 is provided at a point contiguous to the lower edge forming the opening 14 with a notched portion 16, which exposes a portion of the free edge of the flange 12 so that a finger may be readily engaged with this flange when it is desired to move the member 11 to its operative position. In so doing, said member is first moved longitudinally and upwardly with respect to the base plate until the projections 13 engage the upper end of the offset portion 8 adjacent the opening 14. When in this position the member 11 may be swung outwardly and downwardly about the projections 13 as pivots until the portion of the member 11 adjacent said projections engages the lower edge of the opening 14, as shown in Figure 1. The bottle cap 10 is then engaged with the flange 12 and offset portion 8, as shown in said figure, and by moving the bottle to the dotted line position it will be obvious that the cap may readily and quickly be removed from the bottle.

What is claimed is:

1. In a bottle cap removing device, an element having means to secure it to a wall or other support, and a cap removing element slidably and pivotally engaged with the first named element and movable to a closed inoperative position approximately 105
- 110

parallel with the plane of the first named element and to a cap removing position projecting at an angle to said plane.

2. In a bottle cap removing device, an element having means to secure it to a wall or other support, and a cap removing element formed at one end with an inturned flange to engage a cap, said cap removing element being slidably mounted relative to the first named element and having a pivotal engagement at its opposite end with said first named element when moving to operative and inoperative positions.

3. In a bottle cap removing device, an element secured to a wall or other support and forming therewith a compartment, and a cap removing element normally recessed within said compartment and having sliding and pivotal engagement with the first named element and movable to a cap removing position at an angle to said first named element.

4. In a bottle cap removing device, a base plate, and a cap removing element having a flange at one end engageable with said

plate to support said element in its inoperative position and engageable with a cap when in its operative position.

5. In a bottle cap removing device, a base plate, and a cap removing element having a flange at one end engageable with said plate to support said element in its inoperative position and engageable with a cap when in its operative position, said element having longitudinal and pivotal movements with respect to said plate when adjusted to its operative position.

6. In a bottle cap remover, a base plate having an offset portion forming a recess, said offset portion being provided with an opening, a cap removing member mounted within said recess and provided with a flange at one end engageable with an edge of said offset portion forming said opening to support said member in position within said recess, said member having longitudinal movement in said recess and a pivotal movement with respect to said plate when adjusted to its operative position.

TURNER C. RUSH,
